UNITED STATES PATENT OFFICE

LOUIS LA VECK, OF BROOKLYN, NEW YORK

PAPER NAPKIN, TOWEL, AND THE LIKE

Application filed March 26, 1930. Serial No. 438,947.

The invention relates to paper napkins, paper towels and the like, and has for its object to provide napkins, towels and the like, which are folded in a novel manner to permit the same to be easily removed from an available supply or readily withdrawn in independent succession from a suitable container. Other more specific objects of the invention will appear from the description hereinafter and the features of novelty will be pointed out in the claims.

In the accompanying drawing, which shows examples of the invention without defining its limits, Figs. 1, 2, 3, 4 and 5 are views illustrating the paper napkin, towel or the like at various successive stages in the folding thereof; and Figs. 6 and 7 are opposite face views of another form of said folded napkin, towel or the like.

For purposes of simplicity and for no other reason, the description hereinafter has been restricted to paper napkins with a distinct understanding that this term is intended to include paper towels and other devices which may be included in the general class to which the present invention relates. The paper napkin may be made of any suitable material, but is preferably constructed of crepe paper in the form of a rectangle of predetermined dimensions in which the grain of the crepe preferably runs lengthwise of the rectangle, as shown in Fig. 1. In this figure the napkin is indicated at A and the grain of the crepe is designated as B. In folding the napkin in this form the lower end portion C thereof is folded on the dotted line D upon the main portion of the napkin A, as indicated in Fig. 2. After this has been done, the upper portion E of the napkin is folded

on the dotted line F to the position indicated in Fig. 3. The folding lines D and F are so located with respect to the upper and lower ends of the napkin and relatively to each other that the end edges G of said napkin will be spaced apart, as shown in Fig. 3. The folding of the napkin is completed by folding the right hand portion H of the napkin in Fig. 3 inwardly upon the folding line I to the position shown in Fig. 4, after which the left hand portion J of said folded napkin

is folded inwardly in the opposite direction upon the folding line K to a position in which it overlaps the previously folded portion H as shown in Fig. 5, which represents the completely folded napkin. In this completely folded condition the spaced edges G of the napkin provide a bottomed groove L extending transversely of the folded napkin upon opposite faces thereof; in other words, the edges G are capable of being easily picked up by the finger of the person desiring to unfold the napkin, this picking up being facilitated by that portion of the folded napkin which lies beneath and forms a bottom for the groove L.

In the form shown in Figs. 6 and 7 the napkin is folded in the same way as indicated in Figs. 1, 2 and 3, but the opposite end portions of the napkin, instead of being folded inwardly over and upon each other, as shown in Fig. 5, are folded inwardly so as to lie upon opposite faces of the folded napkin, as clearly shown in said Figs. 6 and 7. In this form of the folded napkin, the edges G' corresponding to the aforesaid edges G, are exposed only upon one face of the folded napkin, which accordingly includes but one exposed transverse groove L' upon the one face of the folded napkin. With this form, the edges G' are available upon only one face for picking up to bring about the unfolding of said napkin, which in all other respects corresponds to the form first described.

If the form of folded napkin shown in Figs. 6 and 7 is utilized, it is simply necessary to render that face of the folded napkin on which the transverse groove L' appears accessible, so that the opposite edges G' of the folded napkin may be rendered available for its removal from the supply.

From the above it will be seen that the novel method of folding the napkins provides free transverse edges enabling individual napkins to be easily removed from a supply thereof or withdrawn from a carrier or its equivalent; the character of the fold is such that the napkin is automatically unfolded coincidentally with its removal from a supply or its withdrawal from the carrier. As previously stated the folded napkins illus-

trated and described herein are self-supporting in an upright position, because of the fact that the grain of the crepe runs lengthwise of the folded napkins in contradis-
5 tinction to existing folded napkins made of crepe paper in which the grain of the crepe runs crosswise; such existing folded napkins collapse easily and require rigid supports to maintain them in upright positions in con-
10 tainers or the like. The novel folding of the napkin enables the stock to be run faster on the folding machine than is possible with napkins folded in existing ways, this being due to the fact that the character of the novel
15 fold requires no intermittent motion in the folding machine to effect the folding of the napkin. It is also possible to use a cheaper grade of material in the novel folded nap-
kin illustrated and described herein, because
20 of the fact that the novel folding permits easy removal of the napkins from a container without tearing thereof; existing napkins require a better stock to prevent such tearing, because of the additional effort required in
25 the removal of such napkins resulting from the manner of folding the same.

In order to avoid misunderstanding, it is repeated that even though the description is limited to paper napkins, it is intended to in-
30 clude paper towels and other devices included in the general class to which the instant invention relates. The same remarks apply with equal force to the claims, and it is to be understood that the latter are intended to
35 include all devices which may come in the general class in which paper napkins are in-
cluded.

Various changes in the specific forms shown and described may be made within the scope
40 of the claims without departing from the spirit of the invention.

I claim:

1. A napkin of crepe paper having oppo-
45 site end portions folded toward each other upon one face of the napkin with the opposed edges of said folds spaced apart in the folded condition, and folded toward each other transversely of said first folds upon the opposite face of said napkin to cause said spaced
50 opposed edges to provide bottomed transverse grooves upon the opposite faces of said folded napkin to facilitate unfolding thereof, the folding being so arranged that the grain of the crepe runs lengthwise of the folded nap-
55 kin to reduce the tendency thereof in its folded condition to flex upon itself.

2. A napkin of rectangular form having its single ply folded on spaced parallel lines into surface engagement with one face of
60 said napkin to form adjacent two ply sec-
tions projecting toward each other and hav-
ing their opposed free edges separated from each other, and folded on parallel transverse lines extending at right angles to said first
65 folding lines to provide transverse folded

portions located in overlapping relation upon that portion of the opposite face of said folded napkin lying between said transverse folding lines.

In testimony whereof I have hereunto set
70 my hand.

LOUIS LA VECK.
